HOT PLATE

Cloyd L. Betzer, Kankakee, Ill., assignor to Thermolyne Corporation, Dubuque, Iowa, a corporation of Illinois

Filed Aug. 5, 1968, Ser. No. 13,020

Term of patent 14 years

Int. Cl. D7—04

U.S. Cl. D81—10

FIG. 1 is a front perspective view of a hot plate embodying the design of the present invention;

FIG. 2 is a front elevation view of the hot plate;

FIG. 3 is a rear elevation view of the hot plate;

FIG. 4 is a side elevation view of the hot plate, the two side views being identical;

FIG. 5 is a plan view of the hot plate; and

FIG. 6 is a front perspective view, similar to FIG. 1, of a hot plate embodying another form of the design of the invention, to which FIGS. 3, 4, and 5 apply in the same sense as to the hot plate of FIGS. 1 and 2.

I claim:

The ornamental design for a hot plate, substantially as shown and described.
